UNITED STATES PATENT OFFICE.

RIVERIUS MARSH, OF NEW BRUNSWICK, NEW JERSEY.

DESIGN FOR A CHIMNEY FOR LAMPS.

SPECIFICATION forming part of Design No. 30,081, dated January 31, 1899.

Application filed June 15, 1898. Serial No. 683,538. Term of patent 7 years.

To all whom it may concern:

Be it known that I, RIVERIUS MARSH, a citizen of the United States, residing at New Brunswick, in the county of Middlesex and State of New Jersey, have invented and produced a new and original Design for Chimneys for Lamps; and I do declare the following to be a full, clear, and exact description of the same, reference being had to the accompanying drawing, forming a part thereof.

My invention relates to a new, novel, and graceful cylindrical chimney for lamps, which differs in proportions from other chimneys, the leading features of which consist in a vertical base, above which rising side walls merge into a globular open-top dome, having an expanding curved rim encircling the same.

In the said drawing letter B refers to the base of said chimney for lamps, which is vertical. Gradually the side walls above said base expand in elevation and then converge into a globular dome, (designated by letter A,) which dome has an open top encircled by expanding curved rim, (designated by letter A',) which forms the apex of said chimney. 25

What I claim is—

The design of a chimney for lamps substantially as herein shown and described.

In testimony whereof I affix my signature in presence of two witnesses.

RIVERIUS MARSH.

Witnesses:

GEORGE SCHMIDT,
W. G. SCHERRER.
